US00D728884S

(12) **United States Design Patent**
Waffensmith et al.

(10) **Patent No.:** **US D728,884 S**
(45) **Date of Patent:** **** May 5, 2015**

(54) **LINER FOR PAINT ROLLER BUCKET**

- (71) Applicant: **Bercom International, LLC**, Chanhassen, MN (US)
- (72) Inventors: **Jeffrey B. Waffensmith**, North Oaks, MN (US); **Ryan D. Jordan**, Buffalo, MN (US)
- (73) Assignee: **Bercom International, LLC**, Chanhassen, MN (US)
- (**) Term: **14 Years**
- (21) Appl. No.: **29/486,816**
- (22) Filed: **Apr. 2, 2014**
- (51) LOC (10) Cl. **07-07**
- (52) U.S. Cl.
USPC **D32/54**
- (58) **Field of Classification Search**
